SYRINGE FOR APPLYING HEAT-FLUENT IMPRESSION COMPOSITION TO DENTAL IN-LAY PREPARATIONS AND THE LIKE, AND IMPRESSION-MATERIAL CARTRIDGE FOR USE THEREIN

Henry F. Boeger, Beverly Hills, Calif., assignor to Surgident, Ltd., West Los Angeles, Calif., a corporation of California.

Application November 17, 1947, Serial No. 786,526

7 Claims. (Cl. 128—215)

1

This invention relates to means for utilizing heat-fluent dental impression compositions, such as hydrocolloid compositions of the agar-agar type, for the purpose of taking impressions of relatively small cavities or tooth-preparations, as in the technique of producing dental inlays, and pertains particularly to a construction which provides for facile utilization of such compositions by the dentist or technician in a manner such as not only to produce the desired impression but also to prevent discomfort both to the patient and the technician which normally may result from the use of heated appliances and materials.

These compositions, as is well known, have the characteristic of congealing to a resilient solid condition at a temperature at or near body temperature, when cooled to such congealing temperature from a heated, fluent condition.

One of the particular objects of the invention is to provide a syringe construction, and an impression-material cartridge for use therein, which will enable the dentist or practitioner to dispense a desired quantity of heat-fluidized impression composition into the desired location in the patient's mouth without danger of contacting the patient with any object which has been heated to a point such as to be unbearable upon or injurious to the sensitive mouth tissues.

A further object of the invention is to provide a syringe of the type above set forth, which can be manufactured and made available to the dentist or other practitioner at a nominal cost, as compared with comparable devices which have heretofore been available.

A further object of the invention is to provide an impression-material cartridge element for use in the syringe member above-described, which may be directly immersed in a heating fluid such as water for the purpose of rendering the contained impression-material properly fluent, after which the cartridge may be inserted within the syringe and the contained material made available for immediate extrusion or dispensing into the desired cavity or dental preparation.

Prior to the conception of my invention, it has been the practice in the dental art, where a heat-fluent impression material of the character of an agar-agar hydrocolloid is to be employed for taking so-called "inlay" impressions, to insert fragments or pieces of solidified impression-material into a more-or-less conventional syringe, provided with a hollow discharge needle at one end and adapted to receive a conventional plunger operating in a cylindrical cavity, put the plunger in place so as to close the cylindrical cavity, and place the entire syringe in boiling water and boil

it for a sufficient time to render the contained impression-material suitably fluent. When the impression-material has been so heated within the syringe, as above-described, the dentist removes the syringe from the hot water, and extrudes the fluent material through the mentioned needle into the desired dental preparation, and in view of the fact that many of these preparations are located in relatively inaccessible spots within the mouth, it is not uncommon for the dentist to inadvertently allow the syringe member to come into contact with the mouth tissues, often with a resulting involuntary movement on the part of a patient which is sufficient to seriously interfere with the successful impression-taking operation, and is in any case rather detrimental to good doctor:patient relations. This practice, above-described, is also objectionable from the standpoint of the maintenance of proper conditions of sterility, resulting from the handling of the impression composition in its solidified form, loading the syringe, etc., inasmuch as the boiling period for converting the solidified impression-material to its desired fluent condition may not in all cases be adequate to insure complete sterilization.

According to the practice of the preparation of inlay impressions utilizing the syringe and impression-material cartridge of the present disclosure, the syringe structure per se may have been thoroughly sterilized and cooled to a usable temperature prior to its use by the dentist, and when the dentist desires to take an inlay impression he has merely to place the cartridge of this invention in boiling water, boil it for a length of time sufficient to thoroughly fluidize the contained impression composition, insert the impression-material cartridge bodily into the syringe, and extrude the material through an associated needle member without ever having had to expose the contents to the atmosphere. Even though the cartridge itself is near the boiling point of water, or has been cooled off only to a point where it is still fluid but sufficiently cool to be discharged into the inlay preparation, the heated cartridge and its material is disposed within a syringe member which is at relatively normal temperature, so that if the syringe should come into contact with the patient's mouth there will be no burning sensation. Furthermore, the syringe being at a normal or relatively low temperature, there is no discomfort to the dentist as the syringe is put into use, and for this reason the dentist is able to take the desired impression with greater stability and manual dexterity.

The device of this invention comprises, essen-

trially, a syringe having an elongated casing member or barrel and a coacting plunger member, such barrel being adapted to receive an elongated cartridge comprising a capsule containing a quantity of the impression composition. The cartridge capsule has an open end through which the plunger member is adapted to be extended into contact with a sealing plug which is provided within the capsule for the dual function of providing a substantially hermetic closure for the cartridge, and of serving as a piston member against which the plunger may act in producing the desired extrusion of the contained material for use.

The material-containing cartridge may be provided with a discharge duct or needle secured thereto having a discharge passage communicating with the position of the contained material, through which the heat-fluidized material may be extruded or dispensed for use, and the barrel of the syringe may be provided with an elongated slot through which the discharge duct may extend as the cartridge is inserted in the syringe. Alternatively, the cartridge capsule may be formed of a material which is readily subject to puncture, so that a discharge needle may be inserted through the side wall of the cartridge into communication with the contained impression material after the cartridge is incorporated in the syringe.

The above and other features of this invention will be brought out in the ensuing description of certain preferred embodiments thereof, or will be apparent from such description, having reference to the accompanying drawings, in which:

Fig. 1 is a perspective view of the assembled syringe and cartridge of this invention, ready for use in taking an inlay impression;

Fig. 2 is partly broken away side elevation of a form of cartridge which may be utilized in the assembly shown in Fig. 1;

Fig. 3 is a partly sectional longitudinal view of the assembled syringe and cartridge of Fig. 1, showing the internal structure of the syringe with the cartridge inserted therein as it is employed for taking the impression, with the initial insertion position of the cartridge being shown fragmentarily in dot-dash lines; and

Fig. 4 is a fragmentary sectional view of a modified form of cartridge and syringe construction, corresponding to the lower end of the sectional showing in Fig. 3, on an enlarged scale.

Referring to the drawings, particularly Figs. 1 through 3, the syringe structure of this invention may comprise an elongated cylindrical casing 1, formed of metal or, more preferably, a material of relatively low heat conductivity, such as a synthetic resin, provided with a finger grip member 2 thereon having a cylindrical opening 3 adapted to fit rotatably about the casing 1. The grip member 2 is provided with a pair of diametrically disposed finger grip portions 4 and is adapted to engage upon an annular shoulder 5 on the open end 6 of the casing 1 as at 7.

The casing 1 is provided with a cylindrical chamber 1a adapted to receive a cartridge C comprising a capsule 8 containing the desired impression material, the capsule 8 having generally cylindrical side walls 9, an open end 10, and an end wall 9a at the opposite end. A body of heat fluent impression-material is provided within the lower portion of the capsule 8, as at 11, and is sealed therein through the agency of a closure plug or stopper 12 which is preferably formed of a resiliently compressible material such as rub-

ber, and which is placed within the capsule 8 in substantial abutment with the body 11, as at 12a, to the substantial exclusion of extraneous air.

5 In the form of construction shown in Figs. 1 through 3 the cartridge C is provided with a fixed discharge needle 13 provided with a dispensing passage 14 and having a flange portion 15 molded into the side wall of the capsule 8 adjacent the lower end thereof, such capsule side wall being provided with an opening 16 communicating with the passage 14.

The cartridge C is adapted to fit within the cylindrical casing 1 by insertion thereof through the open end 6, after the manner shown in dot-dash lines at C' in Fig. 3, and in order to accommodate the needle 13, which extends outwardly from the cartridge at an angle to the length of the cartridge, a slot 17 may be provided in the side wall of the casing 1 extending from adjacent the other end of the casing toward the position of the finger grip member 2, and approaching into sufficient proximity with the latter to permit the needle to be inserted in the slot from the interior of the casing when the cartridge is tilted to the dotted line position. The cartridge may then be brought into alinement with the casing member 1 and moved longitudinally within the chamber 1a, toward and into engagement with the other end 8a of said casing member, which provides a shoulder or abutment to limit such movement and hold the capsule 8 against movement during extrusion of the contents thereof as described hereinafter.

35 The syringe structure also comprises a plunger member 18, provided with a hand grip portion 19 and having a push rod 20 adapted to extend into the cavity 21 of the cartridge capsule 8 and to make contact therein with the closure plug 12. 40 The relative length of the cartridge C and the casing 1 is preferably such that when the lower end of the cartridge is seated in the lower end of the casing, the upper end 22 of the cartridge extends outwardly beyond the open end 6 of the casing so as to permit ready and unscreened access to the cavity 21 of the cartridge capsule. The hand grip portion 19 of the plunger member 18 may be shaped as illustrated or of other convenient shape, but of course that terminal portion 45 of the push rod 20 which extends into the cavity 21 of the capsule 8 must be proportioned to provide an annular space between itself and the casing member 1 sufficient to receive the wall 9 of the capsule, said annular space being occupied by said wall 9 when the cartridge is in operative position within the casing 1, as shown in Fig. 3. Thus, the radius of said terminal portion of push rod 20 is less than the radius of the inner bore or chamber 1a of casing 1, by an amount approximately equal to the thickness of the capsule side wall 9.

To seal off and protect the exposed end of the discharge needle 13 prior to use a cap 23 may be provided, if desired. Said cap may be of plastic or rubber, and is preferably formed by dipping the end of the needle in a solution of plastic sealing material.

To install and utilize a cartridge containing heat fluent impression-material with the syringe assembly as above described, the cartridge C, with stopper 12 in place in abutment with the body 11 of the material, is placed in boiling water and heated until the contained material is fluidized and the needle 13 is sterilized. The plunger 18

is removed from the casing 1, the cap 23 (if present) is removed from the needle 13, and the cartridge C is inserted in the bore or chamber 1a of the casing by tilting the cartridge as shown in dot-dash lines in Fig. 3 to permit the needle 13 to enter the upper end of the slot 17, by which the needle is guided to its operative position at the lower end of the casing. The plunger 18 is then inserted in the bore or cavity 21 of the cartridge capsule 9 so that the terminal portion of push rod 20 is brought into contact with the stopper 12. When the needle 13 has been placed in proximity with the desired dental preparation, manual pressure upon the finger grips 4 and hand grip 19 will force the stopper 12 downwardly, as a piston, and will cause the heat-fluidizable material to extrude through the dispensing passage 14 of the needle. The dentist or technician will find, to his convenience, that the casing 1 and the grips 4 and 19 are relatively cool, that the contents of the cartridge have not been exposed to unsterile conditions, and that the finger grips 4 and hand grip 19 are rotatable to any desired angle with respect to the needle 13 so that the latter may be directed as desired, the plunger 18 nevertheless tending to bind against the stopper 12 when pressure is exerted thereon so that the syringe does not turn accidentally in the operator's hand. The patient will find, to his comfort, that the exposed casing 1 is relatively cool to his mouth tissues.

In Fig. 4 is illustrated a modified form of my invention, having a dispensing needle 26 provided as a separate, attachable unit. The syringe casing 27 has an opening 28 adjacent its closed end and communicating with the inner bore or chamber 29 at a convenient angle. The cartridge C' comprising a capsule 30, which in this modified form is made of moisture-impermeable material which punctures readily, particularly after being heated, such as polyethylene, has a somewhat thickened bottom wall 31 to receive and hold firmly the needle 26. The needle 26 has a sharpened inner end 32 suitable for insertion through the opening 28 and for puncturing the bottom wall 31 of the cartridge 30 to permit fluent materials in the cartridge to pass through a passage 33 in the needle.

With the above-described modified form of device, a number of cartridges C' may be kept on hand, loaded with various compositions of heat-fluidizable material as indicated at 34, and may be heated and used as required. Also a number of needles 26, of various lengths and thicknesses, may be utilized selectively, being inserted through the opening 28 to puncture the cartridge 30 and being withdrawn therefrom when their temporary use is terminated. The casing 1, shown in the preferred embodiment of my invention, is interchangeable with the casing 27, as the needle 26 may equally well be inserted through the lower end of the slot 17. Except as above explained, the two above described embodiments of my invention, including the plunger 18, and the method of use thereof, may be identical.

Having described preferred embodiments of my invention, it will be evident that various changes in the details and arrangement of parts may be made by persons skilled in the art without departing from the spirit and scope of my invention as defined in the claims asserted in this application; and consequently I wish it understood that the foregoing description is considered as being illustrative of, rather than restrictive upon, the appended claims.

I claim:

1. A cartridge structure adapted for use in dispensing a normally solid heat-fluidizable material of the character of hydrocolloid impression composition, which comprises: an elongated capsule formed of substantially moisture-impermeable material and having side wall portions defining a generally cylindrical cavity open at one end and closed at the other end; a body of solid heat-fluidizable material disposed in said cavity in substantially uniform contact with the internal side wall surfaces of said capsule and extending from said closed end to a position intermediate the ends thereof; a resiliently compressible closure plug slidably disposed wholly within said cavity in substantial abutment with said body at said position and being compressively engaged with said side wall portions to form a substantially hermetic seal therewith, said side wall portions projecting beyond the position of said plug towards said open end; and a tubular discharge member secured to a wall portion of said capsule at said closed end and extending outwardly therefrom at an angle to the length of said capsule, said last mentioned wall portion being provided with an opening establishing communication between said tubular discharge member and said cavity.

2. A cartridge structure adapted for use in dispensing a normally solid heat-fluidizable material of the character of hydrocolloid impression composition, which comprises: an elongated capsule formed of substantially moisture-impermeable material and having side wall portions defining a generally cylindrical cavity open at one end and closed at the other end; a body of solid heat-fluidizable material disposed in said cavity in substantially uniform contact with the internal side wall surfaces of said capsule and extending from said closed end to a position intermediate the ends thereof; a resiliently compressible closure plug slidably disposed wholly within said cavity in substantial abutment with said body at said position and being compressively engaged with said side wall portions to form a substantially hermetic seal therewith, said side wall portions projecting beyond the position of said plug towards said open end; and a tubular discharge member secured to a wall portion of said capsule at said closed end and extending outwardly therefrom, said discharge member being provided at its inner end with a flange secured within said last mentioned wall portion of the capsule, and said wall portion being provided with an opening establishing communication between said tubular discharge member and said cavity.

3. A cartridge structure adapted for use in dispensing a normally solid heat-fluidizable material of the character of hydrocolloid impression composition, which comprises: an elongated capsule formed of substantially moisture-impermeable material and having side wall portions defining a generally cylindrical cavity open at one end and closed at the other end; a body of solid heat-fluidizable material disposed in said cavity in substantially uniform contact with the internal side wall surfaces of said capsule and extending from said closed end to a position intermediate the ends thereof; a resiliently compressible closure plug slidably disposed wholly within said cavity in substantial abutment with said body at said position and being compressively engaged with said side wall portions to form a substantially hermetic seal therewith, said side wall portions projecting beyond the

position of said plug towards said open end; and a tubular discharge member secured to a wall portion of said capsule at said closed end, communicating at its inner end with the cavity of said capsule, and extending outwardly from the capsule at an angle to the length of the capsule.

4. A construction for use in dispensing a normally solid heat-fluidizable material of the character of hydrocolloid composition, which comprises, in combination: a casing of circular cross section having an elongated chamber open at one end of the casing and provided with an opening in the wall thereof adjacent the other end of the casing; a finger grip member on said casing adjacent said one end thereof in position to constrain said casing member against longitudinal displacement thereof in a direction such as to force said one end past said grip member; an elongated cartridge comprising a capsule formed of substantially moisture-impermeable material and having a wall defining an elongated cavity open at one end and closed at the other end, said cartridge being adapted to be disposed in said cylindrical chamber with its open end located adjacent the open end of said casing and with its closed end seated at the other end of said casing, and said capsule containing a body of heat-fluidizable material disposed therein; said cartridge having a resiliently compressible closure plug slidably disposed within said capsule adjacent said open end of the capsule in substantial abutment with said body of material and compressively engaged with the wall of said capsule to form a seal therewith, and said cartridge being provided at its closed end with a tubular discharge member secured to the wall of said capsule and projecting outwardly therefrom and adapted to extend through said opening in the wall of the casing when said cartridge is disposed in said chamber; the wall of said capsule being provided with an opening establishing communication between said tubular discharge member and said cavity; and a plunger member having an elongated push rod of a diameter smaller than the internal diameter of said casing and adapted for insertion within the cylindrical cavity of said capsule.

5. A construction for use in dispensing a normally solid heat-fluidizable material of the character of hydrocolloid composition, which comprises, in combination: a casing of circular cross section having an elongated chamber open at one end of the casing and provided with an opening in the wall thereof adjacent the other end of the casing; a finger grip member on said casing adjacent said one end thereof in position to constrain said casing member against longitudinal displacement thereof in a direction

such as to force said one end past said grip member; an elongated cartridge comprising a capsule formed of substantially moisture-impermeable material and having a wall defining an elongated cavity open at one end and closed at the other end, said cartridge being adapted to be disposed in said cylindrical chamber with its open end located adjacent the open end of said casing and with its closed end seated at the other end of said casing, and said capsule containing a body of heat-fluidizable material disposed therein; said cartridge having a resiliently compressible closure plug slidably disposed within said capsule adjacent said open end of the capsule in substantial abutment with said body of material and compressively engaged with the wall of said capsule to form a seal therewith, and said cartridge being provided at its closed end with a tubular discharge member secured to the wall of said capsule and communicating at its inner end with the cavity therein, said tubular discharge member projecting outwardly from the capsule and being adapted to extend through said opening in the wall of the casing when said cartridge is disposed in said chamber; and a plunger member having an elongated push rod of a diameter smaller than the internal diameter of said casing and adapted for insertion within the cylindrical cavity of said capsule.

30 6. A construction as set forth in claim 5, in which the opening in the wall of the casing comprises an elongated slot extending from a position adjacent said other end of the casing toward the open end thereof, and the tubular discharge member extends outwardly from the cartridge at an angle to the length of said cartridge so as to project slidably through said elongated slot during movement of said cartridge within said casing to a position to engage said other end of the casing.

35 7. A construction as set forth in claim 5, said finger grip member being rotatably mounted on said elongated casing for relative rotation about an axis extending longitudinally of said casing.
